CLAIM

The ornamental design for a vehicle seat, as shown and described.

DESCRIPTION

Vehicle seat

11.1 : Perspective

11.2 : Front

11.3 : Back

11.4 : Top

11.5 : Bottom

11.6 : Left

11.7 : Right

11.8 : Partial enlarged view of solid line of view 11.2

11.9 : Partial enlarged view of solid line of view 11.7

(Continued)

The dashed-dotted-dashed lines represent the boundary lines of the claimed designs; the broken lines showing are for the purpose of illustrating environmental structures and form no part of the claimed designs.

1 Claim, 7 Drawing Sheets
